US00D655736S

(12) United States Design Patent
Barley et al.

(10) Patent No.: US D655,736 S
(45) Date of Patent:  Mar. 13, 2012

(54) SCOUTING CAMERA

(75) Inventors: Christopher B. Barley, Grand Prairie, TX (US); James Brandon Roach, Grand Prairie, TX (US)

(73) Assignee: WGI Innovations, Ltd., Grand Prairie, TX (US)

() Term: 14 Years

(21) Appl. No.: 29/396,611

(22) Filed: Jul. 1, 2011

(51) LOC (9) Cl. 16-01

(52) U.S. Cl. D16/203; D16/218

(58) Field of Classification Search D16/200-204, D16/208, 218; 348/143, 373-376; 396/427, 396/535-541

See application file for complete search history.

(57) CLAIM

The ornamental design for a scouting camera, as shown and described.

DESCRIPTION

FIG. 1 is a front, top and left side perspective view of a scouting camera showing our new design;

FIG. 2 is a front elevational view thereof;

FIG. 3 is a top plan view thereof;

FIG. 4 is a left elevational thereof;

FIG. 5 is a rear elevational view thereof;

FIG. 6 is a right elevational view thereof; and,

FIG. 7 is a bottom plan thereof.

The portions of the camera in broken lines are shown for illustrative purposes only and form no part of the claimed design.

1 Claim, 7 Drawing Sheets
